UNITED STATES PATENT OFFICE.

HENRY RICHARD SHIRLEY, JR., OF GEELONG WEST, VICTORIA, AUSTRALIA.

MEANS FOR STORING, DISPLAYING, AND ADVERTISING.

1,250,038.

Specification of Letters Patent. Patented Dec. 11, 1917.

Application filed September 15, 1916. Serial No. 120,309.

To all whom it may concern:

Be it known that I, HENRY RICHARD SHIRLEY, Jr., a subject of the King of Great Britain and Ireland, &c., residing at Geelong 5 West, in the State of Victoria, Commonwealth of Australia, have invented certain new and useful Improvements in Means for Storing, Displaying, and Advertising; and I do hereby declare the following to be a 10 full, clear, and exact description of the invention, such as will enable others skilled in the art to which it appertains to make and use the same.

My invention relates to means for attractively storing, displaying, and advertising articles, and comprises holders to be used chiefly on shop counters, and in shop windows, to promote the sale and quick delivery of the articles, which will include many 20 kept by grocers, tobacconists, druggists, confectioners and so forth. When an article is in a tinned or like boxed form it will suit this invention best.

In carrying this invention into effect I 25 make a holder having one or more vertical or other tubes or magazines, each to hold, upon a spring raised carrier, superposed articles, for example boxes of matches, cigarettes, tobacco, shoe polish, food, or so on. 30 The outermost or uppermost article within the magazine can be easily removed, whereupon the article within the magazine which adjoined the removed one will automatically take the latter's place.

The magazine will be of any suitable 35 length, cross section, ornamentation and materials. Material which is transparent can obviously be used for various parts.

My invention provides for supporting and 40 if desired holding an article over the magazine, either opened or closed, also means to indicate the number of tins or articles in a magazine which is not full.

In my preferred construction the removal 45 of an article may be effected either by pushing or pulling it out whether the top of the article be tangible or not.

The articles in a magazine will often (but need not) be the same, and need not all have 50 casings of the same material; but the latter must permit the articles to leave the magazine easily notwithstanding friction.

The carrier aforesaid has in some cases an outwardly projecting handle or means by 55 which it may be moved along the magazine.

The foregoing and other features of the

invention will be explained by reference to the accompanying drawings in which simple constructions are illustrated.

The invention is not limited to the particular designs, proportions, or numbers of parts shown, as modifications may be made to suit the articles to be put in the magazines, and the general circumstances of use, but features covered by one or more of my subsequent claims will still be retained.

In the drawings, Figure 1 shows a view (with parts broken away and omitted) of a holder having a display fitting over its magazine which stands vertically and the top of which can support one or more articles. This figure is partly in perspective with the lower end and a higher part of the magazine omitted to show an internal spring, and with a foot to which the magazine is secured shown in vertical middle section. Fig. 2 is a perspective rear view of the upper part of a magazine showing part of the spring projecting. In this view dotted lines show a carrier upon the spring, and several articles upon the carrier within the magazine. Fig. 3 is a rear elevation of part of a magazine which is pivotally connected to a mount which allows the magazine to be adjusted into a variety of positions.

Fig. 4 is a plan and Fig. 5 is an elevation of a magazine upper end having an adjustable fitting which can be raised, lowered or removed, and upon which one or more articles can be placed at will, but which is at will intended to allow full view of the highest article under it.

Fig. 6 is a transverse section through one form of magazine, which is fitted with an advertisement or display sheet which can be removed at will. Fig. 7 is a perspective rear view of a cylindrical carrier or lift plate, and Fig. 8 shows a rectangular carrier over two springs, the invention not being limited as to the number of springs.

Fig. 9 is a perspective view of the upper part of a rectangular magazine held upon which is an open box of matches, the magazine containing unopened boxes, the uppermost of which is easily slidable to the front or rear for sale or other purpose.

I do not illustrate a construction comprising two or more magazines in combinations, but such would be useful and could obviously be made. It might contain, for example, in respective magazines, different makes of cigarettes, or tobacco.

Part 1 in the drawings indicates a magazine. It is tubular and is arranged in some cases so that it can be supplied with articles through its base, but it can always be supplied at its top. 2 is a removable cap on the magazine base in Fig. 3; 3 are screws entering or bearing on the magazine base in Fig. 1. These screws pass through a foot 4 which is recessed to inclose the lower end of the magazine, which, when the foot is detached, is open, in my preferred construction, allowing of easy access to the magazine interior. When provision is not made for access to a magazine interior at its bottom, then the top of the magazine which is wholly or partly open, is used for the insertion of articles. 6 indicates a wholly open top, and 6^a a partly open top.

In each magazine I provide one or more springs 7 having any suitable lower support the spring in Figs. 1 and 3 resting on the magazine bottom, and at the top supporting a lift or carrier 8 shown with a handle 8^a, which projects outside the magazine as a means to enable the carrier to be pressed down or raised by hand as may from time to time be desired. Each spring is in expansion when the magazine is empty, and is in greater or less compression when the magazine contains articles on the carrier. The spring is adapted to feed all the articles that can be put on it to the magazine top for successive removal.

The way to introduce an article at the top of a magazine depends on the details at the said top. In Fig. 1 there is a fixed top plate 10, and the magazine wall has a recess 9 with sides 16. In that case the way is to insert it horizontally, as per arrow a, on the carrier which can be ready depressed. To insert another article, the first article is pressed down, and the second is inserted horizontally upon the first one, and this process can be continued until the magazine is full, with the spring or springs considerably compressed. The last inserted article will then press against the under side of the plate 10 or magazine head. 10 is a plate which is gapped to allow a great deal of the top of the uppermost article in the magazine to be displayed. 11 is a wire fitting through which almost all of an article top would be displayed to view. 12 will be supposed to represent any top which prevents the box or article under it from being pressed higher by the action of the spring on the carrier.

In each case articles can be placed and displayed upon the head 10, 11, or 12. An article illustrated at 13 is an open box, held over magazine 1 by framing 14, 15 connected to the magazine.

The magazine rear has an opening of any suitable width behind opening 9, at 17. 65 Articles can be pushed in the direction of

arrow b by pressure through opening 17 and be caused to emerge at 9. Such pressure will generally be effected by an attendant behind a counter on which the magazine is set. An article may be removable either to the front or rear from a magazine, as is evident from Figs. 4 and 5, and in the form in Fig. 9 I intend to provide for such removal so that a shop attendant can move an article from him, or toward him, out of the magazine. The uppermost article in various magazines is marked c, under which in succession are shown articles d, e, f in Fig. 2. The article under article c is, as a rule, not removable until the latter article has been removed, because the depth of the opening 9 in the wall or part of the magazine under the head is more than the depth of article c, but less than that of articles e and d combined. When a magazine head is adjustable as in Figs. 4 and 5, the removal of a plurality of articles at once may be provided for. An advantage of a raisable or lowerable head to a magazine is that articles can be used below such heads which would be too deep to be usable in magazines having exits of fixed depth as at 16 in Fig. 1 or 16^a in Fig. 9.

The magazine top may have any suitable means of connection to the magazine such as sockets 18, 19, with thumb screws. By moving a top 11 clear of the magazine top 6, the magazine can be very quickly stored with articles. Sockets may be attached to a magazine in any suitable numbers and positions. In Fig. 9, socket 20 is at a corner of the magazine. In Fig. 1 a socket 18 carries an adjustable arm 27 having a connection 28 to a display fitting 29, shown with a lip 30 but which may be of any suitable kind. This fitting permits of prices, advertisements, circulars and goods being prominently shown and a mirror may form part of fitting 29.

Carrier 8 has in some cases a flange as 8^b, which in some cases is of greater depth than that of side 16 or 16^a of opening 9, thus preventing temporary displacement of the carrier when in its highest position in the cases of Figs. 1 and 9. The side recesses 115 allow of an article being grasped at its sides in order to remove it, there being then no necessity to touch the article top for that purpose.

When the handle 8^a (which may be screwed on or otherwise arranged) is provided a slot 33 of any suitable length is also provided in the magazine, to allow the handle to project. Slot 33 is useful to allow of viewing the articles and other parts in the magazine. The slot has in some cases a scale marked alongside it, as at 32 with at will numbers to indicate the number of articles in the magazine—see Fig. 3.

To allow of the attachment (removably) 130

of material displaying any advertisements or facing desired, such as sheet 23 in Fig. 6 and partly shown in Fig. 2, I provide in some cases flanges or clips 21, 22 under 5 edges of which edges of the said material will be retained.

In some cases a magazine having no slot 33 or flanges 21, 22, will be employed. In 10 Fig. 3 a pillar 26 on foot 31 is, in my preferred form revoluble, and has jointed to it adjustable arms 25, having the magazine pivoted thereto at 24. Foot 4 or 31 may be fixed down as by screwing, or may stand unfixed. It is also feasible to support a magazine against a wall by some simple connection.

Having described this invention, what is claimed by Letters Patent is:—

A storing device comprising a vertically

disposed hollow container having a vertical 20 slot therein, a base having a depression in which the bottom of the hollow container is seated, adjustable means for securing the base to the container, a plunger in the container to force packages to the top of the 25 latter, and a spring interposed between the base and the plunger, means on the upper end of the container for limiting the upward movement of the packages by the plunger, the container having a vertical slot, 30 the walls of which are bent to form guides, in which the edges of an advertising sheet wrapped around the container can be confined.

In witness whereof I have hereunto set 35 my hand.

HENRY RICHARD SHIRLEY, JUNR.
